US00D868061S

(12) **United States Design Patent** (10) **Patent No.:** **US D868,061 S**
(45) **Date of Patent:** **** Nov. 26, 2019**

(54) **WEARABLE ELECTRONIC DEVICE**

(71) Applicant: **Samsung Electronics Co., Ltd.**, Suwon-si (KR)
(72) Inventors: **Byeongcheol Yoon**, Suwon-si (KR); **Jeongrok Park**, Hwaseong-si (KR); **Kyungwan Park**, Suwon-si (KR); **Soyoung Kim**, Suwon-si (KR); **Shiyun Cho**, Anyang-si (KR)

(73) Assignee: **SAMSUNG ELECTRONICS CO., LTD.**, Suwon-si (KR)

(**) Term: **15 Years**

(21) Appl. No.: **29/578,897**

(22) Filed: **Sep. 26, 2016**

(30) **Foreign Application Priority Data**

Mar. 24, 2016 (KR) 30-2016-0013726

(51) LOC (12) Cl. **14-02**

(57) **CLAIM**

The ornamental design for a wearable electronic device, as shown and described.

DESCRIPTION

FIG. 1 is a front perspective view of a first embodiment of a wearable electronic device showing our new design; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a front perspective view of a second embodiment of a wearable electronic device showing our new design; FIG. 9 is a front elevation view thereof; FIG. 10 is a rear elevation view thereof; FIG. 11 is a left side elevation view thereof; FIG. 12 is a right side elevation view thereof; FIG. 13 is a top plan view thereof; and, FIG. 14 is a bottom plan view thereof.

The dashed broken lines in the drawings illustrate portions of the wearable electronic device that form no part of the claimed design.

1 Claim, 10 Drawing Sheets
